UNITED STATES PATENT OFFICE.

LOUIS H. BRINKMAN, OF WEST HARTFORD, CONNECTICUT, ASSIGNOR TO THE WHITLOCK COIL PIPE COMPANY, OF WEST HARTFORD, CONNECTICUT, A CORPORATION OF CONNECTICUT.

APPARATUS FOR BENDING PIPE.

SPECIFICATION forming part of Letters Patent No. 783,716, dated February 28, 1905.

Application filed May 16, 1904. Serial No. 208,094.

To all whom it may concern:

Be it known that I, LOUIS H. BRINKMAN, a citizen of the United States, residing at West Hartford, in the county of Hartford and State 5 of Connecticut, have invented a new and useful Improvement in Apparatus for Bending Pipe, of which the following is a specification accompanied by drawings forming a part of the same, in which—

10 Figure 1 represents a side elevation of my apparatus in operation. Fig. 2 is a central vertical sectional view, on an enlarged scale, of the annular burner. Fig. 3 is an enlarged sectional view of a detail of the burner, showing 15 the attachment of a gas-pipe to the burner. Fig. 4 is a front view of a detail of the upright frame. Fig. 5 represents a front view, and Fig. 6 is a sectional view, on line 66, Fig. 1.

Similar reference figures refer to similar 20 parts in the different views.

The object of my present invention is to provide a simple and automatic apparatus for bending metal pipe, and especially pipe of the larger sizes, without requiring the pipe to be 25 filled to resist any crushing strain incident to the process of bending, and which will enable the pipe to be uniformly and gradually bent by the automatic action of the bending apparatus. To accomplish this result, I provide a 30 support for the pipe, preferably in a horizontal position, by which the pipe is held from displacement while subjected to a bending strain, and while it is so held I feed it longitudinally past a heating apparatus adapted to 35 successively heat limited sections of the pipe. At the same time the advancing end of the pipe is held at a fixed distance from a point concentric with the desired curvature of the pipe, and as the pipe is bent at its heated section 40 and fed past the heating apparatus I provide means for immediately cooling the heated section to preserve its curvature, and I further provide means for determining the curvature of the pipe.

45 Referring to the accompanying drawings, 11 denote vertical posts mounted on a base A. Attached to the posts 11 is mounted a

bracket 2, in which is journaled a grooved roll 3. On the opposite side of the posts 11 a bracket 4 is adjustably attached, in which 50 is journaled a similar grooved roll 5. The brackets 4 are fastened to the posts 11 by the nuts 6 and bolts 7 in the slots 8, so that on loosening the nuts 6 the brackets 4 and roll 5 are capable of vertical movement on the posts 55 11 in order to vary the vertical distance between the rolls 3 and 5. Attached to the brackets 4 and extending vertically is a rod 9, the upper end of which is screw-threaded and passes through a screw-threaded hole in 60 a bar 10, fastened to the post 1. When the nuts 7 on the brackets 4 are loosened, the brackets 4 may be raised or lowered by screwing the nut 11 on the rod 9. By this means the roll 5 may be raised or lowered and the 65 vertical distance between the rolls 3 and 5 varied, as desired, for different sizes of pipe.

At a suitable distance above the bar 10 on the posts 1 a bar 12 is mounted and fastened to the posts 1 by nuts 13 and bolts 14 passing 70 through slots 15, so that the bar 12 can be adjusted vertically when the nuts 13 are loosened. Projecting from the bar 12 are arms 16, in which is journaled a rock-shaft 17. In the center of the rock-shaft 17 is a collar 18, 75 through which passes the screw-threaded end 19 of a radius-rod 20, which is held in the desired position by a nut 20^a. The lower end of the radius-rod 20 is provided with a hook 21, which is inserted in the end 22^a of the pipe 80 22 to be bent. By means of the screw-threaded end 19 and nut 20^a the length of the radius-rod 20 between the rock-shaft 17 and the end 22^a of the pipe may be increased or diminished in order to vary the curvature of the 85 pipe as desired. By loosening the nuts 14 the bar 12 may be raised or lowered as required by the changed length of the radius-rod 20.

On the posts 1 above the roll 3 and between 90 it and the roll 5 brackets 23 are fastened which extend out beyond the position of the roll 5. In the ends of the brackets 23 are bearings 24, in which is journaled an annular

gas-burner 25, by means of which I heat a section of the pipe 22 to render it capable of bending. The annular gas-burner 25 forms no part of my present invention, and is substantially like that described and claimed in my pending application, Serial No. 164,304. By means of the gas-burner 25 I am enabled to heat a portion of the pipe by an annular flame fed by air and gas through the narrow slots 26 and 26^a, Fig. 2, and I cool said heated portion after it is bent by jets of water through the short nozzles 27, the jets of water being applied contiguous to the flame and between it and the advancing end 22^a of the pipe, and the water is supplied to the nozzles 27 from an annular chamber 27^a, which is fed through a pipe 27^b from a similar chamber 27^c, which receives its supply from any source of water-supply through a pipe 27^d. Through the gudgeons 28 of the annular burner 25 I insert screw-threaded pipes 29, to which are fastened, by union-couplings 30, right-angled pipes 31, which receive the gas-supply pipes 32, as shown in Fig. 3, by which I admit gas under pressure to the annular chambers 32^a of the burner 25. Air is admitted through pipes 32^b to an annular chamber 32^c of the burner. The annular burner 25 may be rocked in its bearings 24 to vary the plane of the burner relatively to the axis of the pipe 22, so that by inclining the burner, as shown in Figs. 1 and 2, an elliptical rather than a circular portion of the pipe 22 is heated. By inclining the burner I am able to vary the shape of the bent pipe in cross-section—as, for example, from a circular to an elliptical shape in cross-section. The variation of the annular burner 25 I accomplish by a rod 33, which is attached to a flange 34 at the lower side of the burner 25 and inserted through a block 35 on a bar 36, journaled in bracket 37, which is supported by the frame of the apparatus, and said rod 33 is held from accidental movement by a set-screw 38 in said block, as shown in Fig. 6.

The pipe 22 to be bent is inserted between the rolls 3 and 5 and through the burner 25, and its end 22^a is engaged by the hook of the radius-rod 20, the bar 12 having been adjusted to make the distance between the end of the pipe 22^a and the axis of the rock-shaft 17 equal to the radius of the desired curvature of the pipe. Pressure is then applied to the opposite end of the pipe and in the direction of its length by means of a follower 39, carried by a piston-rod 40 and actuated by an ordinary hydraulic cylinder 41. When the resistance of the heated portion becomes less than the pressure exerted by the piston 40, the pipe will be advanced, and as its forward end is held by the radius-rod 20 it will be bent at its weakened portion on the arc of a circle whose radius is represented by the length of the radius-rod 20, and as soon as the heated section of the pipe is pushed beyond the

burner 25 it will be cooled by the water from the nozzles 27, and its curvature thereby becomes permanently set.

The operation of my device is as follows: The distance between the rolls 3 and 5 being 70 adjusted by raising or lowering the roll 5 to receive the pipe 22, which is to be bent, the pipe is inserted between the rolls 3 and 5 and is fed through the annular burner 25 by the follower 39 and hydraulic cylinder 41. The 75 desired degree of curvature having been determined and the radius of a circle obtained which will embody such degree of curvature, the radius-rod 20 is adjusted by turning the nut 20^a to correspond with the length of said 80 radius, and the bar 12 is raised or lowered to allow the hook 21 on the end of the rod 20 to engage the end 22^a of the pipe to be bent. It is obvious that as the hydraulic cylinder 41 continues to press the pipe forward it will be 85 held from longitudinal movement by the rod 20, and the only direction in which the end 22^a can move is on the arc of a circle with the rod 20 as its radius. This of course necessitates a bend in the pipe, which takes place 90 when the resistance against bending is reduced by heating until it is less than the pressure exerted by the hydraulic cylinder. When the portion inclosed within the annular burner 25 is heated enough to reduce its resistance 95 below the force exerted by the hydraulic cylinder 41, the pipe will be forced forward on the arc of a circle with its radius equal to the rod 20, and that portion of the pipe will have received the desired curvature. As the pipe is 100 advanced beyond the line of flame it passes between the nozzles 27, by means of which it is cooled and further bending at that point prevented. The movement of the pipe also brings a fresh portion into the annular burner, 105 when it is heated as before and the operation is repeated. As considerable pressure may be applied by the hydraulic cylinder it is not necessary that the heating of the pipe proceed very far before the pipe is ready to bend, so 110 that the bending may proceed with comparative rapidity, and excessive heat is not required from the annular burner. It is also 115 obvious that the operation of the apparatus will continue without attention until the pipe is fully bent into the desired curvature. It is also only necessary to adjust the apparatus when a new pipe is inserted of different diameter or which requires to be bent in a different curvature, each pipe being completely and 120 correctly bent without the need of care or attention.

I do not wish to confine myself to the specific construction shown, as minor modifications may be made without departing from 125 the spirit of my invention.

The rolls 3 and 5 are arranged in different vertical planes to resist the bending strain on the pipe, and when the strain is applied by the radius-rod 20 the rolls 3 and 5 serve to hold 130

the pipe from displacement in a vertical plane by their position and also in a horizontal plane by means of their grooved surfaces.

While a hydraulic cylinder affords a convenient method of applying a longitudinal pressure to the pipe, I do not confine myself to such use.

What I claim as my invention, and desire to secure by Letters Patent, is—

- 1. In an apparatus for bending pipe, the combination with a framework, rolls supported by said framework in different planes and adapted to receive the pipe to be bent between them, an annular burner, means for imparting a longitudinal pressure to one end of the pipe to be bent, and means for maintaining the opposite end of the pipe at a constant distance from a fixed point concentric with the desired curvature of the pipe.
- 2. In an apparatus for bending pipe, the combination of a framework, two fixed supports in different planes adapted to receive the pipe to be bent, means for heating a section of the pipe contiguous to one of said supports, means for imparting a longitudinal movement to the pipe between said supports, and means for maintaining the advancing end of the pipe at a constant distance from a fixed point concentric with the desired curvature of the pipe.
- 3. In an apparatus for bending pipe, the combination of a pair of supports in different planes arranged to bear against the pipe to be bent and on opposite sides, means for imparting a longitudinal movement to the pipe between said supports, and means for applying a pulling strain to the advancing end of the pipe toward a point concentric with the desired curvature of the pipe.
- 4. In an apparatus for bending pipe, the combination with a pair of supports in different planes and arranged to bear against opposite sides of the pipe to be bent, of means for imparting a longitudinal movement to the pipe, means for maintaining the advancing end of the pipe at a constant distance from a fixed point and means for applying heat around the entire periphery of the pipe.
- 5. In an apparatus for bending pipe, the combination with a pair of supports in different planes and arranged to bear on opposite sides of the pipe to be bent, means for imparting a longitudinal movement to the pipe, means for maintaining the advancing end of the pipe at a constant distance from a fixed

point, means for heating a section of the pipe between said supports and its advancing end, and means for cooling said heated section as the pipe is moved forward.

6. In an apparatus for bending pipe, the combination of means for imparting a longitudinal movement to the pipe to be bent, means for imparting a bending strain to the advancing end of the pipe, means for continuously and successively heating sections of the pipe, and supports arranged to bear against opposite sides of the pipe to resist the bending strain applied to the advancing end of the pipe.

7. In an apparatus for bending pipe, the combination of a framework, a pair of supports arranged to bear against opposite sides of the pipe to be bent and in different planes, means for moving the pipe longitudinally, means for heating a section of the pipe between said supports and its advancing end, and a swiveled radius-rod engaging the advancing end of the pipe.

8. In an apparatus for bending pipe, the combination with means for supporting the pipe to be bent, means for imparting a longitudinal movement to the pipe, means for imparting a bending strain to the advancing end of the pipe and consisting of a radius-rod engaging the advancing end of the pipe, and means for varying the length of said radius-rod.

9. In an apparatus for bending pipe, the combination of a framework, supports for the pipe to be bent, held in said framework in different planes and arranged to bear against opposite sides of the pipe, means for varying the distance between said supports to receive pipes of different sizes, means for moving the pipe lengthwise, means for imparting a bending strain to the advancing end of the pipe, and means for heating and cooling continuously successive sections of the pipe.

10. In an apparatus for bending pipe, the combination with means for supporting the pipe to be bent, of an annular burner for heating a section of the pipe, and means for maintaining said burner in a plane at an oblique angle to the axis of the pipe.

Dated this 12th day of May, 1904.
LOUIS H. BRINKMAN.
